ONE-PIECE PLASTIC IGNITION HARNESS
FOR GASOLINE ENGINES

William R. Newman, Austin, Tex.

Application March 21, 1947, Serial No. 736,221

1 Claim. (Cl. 123—143)

1

This invention relates to a one piece plastic ignition harness for gasoline engines.

It is an object of the present invention to provide a neat ignition arrangement for a gasoline engine wherein there will be no exposed wires and whereby the ignition system will be made waterproof and not effected by heat, oil or grease and wherein to eliminate replacements due to the fact that the wires have been subject to wear, deterioration and vibration.

Other objects of the present invention are to provide an ignition system which can be assembled at the factory and wherein the wiring will be installed with less chance of there being an error made and wherein the ignition wiring can be installed with less time and labor and further to provide an ignition system which cannot be so readily tampered with.

For other objects and for a better understanding of the invention, reference may be had to the following detailed description taken in connection with the accompanying drawing, in which

Fig. 1 is a front elevational view of the ignition harness embodying the features of the present invention with portions of the same broken away to show the interior of the same.

Fig. 2 is a cross-sectional view taken on line 2—2 of Fig. 1 and looking in the direction of the arrows thereof.

Fig. 3 is a cross-sectional view of the harness taken on line 3—3 of Fig. 1.

Fig. 4 is a transverse cross-sectional view taken on line 4—4 of Fig. 3.

Fig. 5 is a fragmentary side elevational view of the distributor and the portion of the harness extended over the same with portions broken away to show the interior of the harness.

Fig. 6 is a fragmentary and cross-sectional view taken of one of the connections with the spark plug.

Fig. 7 is a transverse cross-sectional view taken on line 7—7 of Fig. 3.

Referring now to the figures, 10 represents a gasoline engine having spark plugs 11 disposed thereon. Wires 12 are to extend from a distributor 13 for connection with the spark plugs 11. According to the present invention, these wires 12 and their terminals 13' are embedded in solid molded plastic with the terminals being at the proper spacings so that they will be seated simultaneously upon the upper ends of the spark plugs 11. Clips 14 are disposed inside of the terminals 13 to obtain perfect contact with the upper ends of the plugs. These clips 14 and wires 12 are

2

soldered to the terminals 13' as indicated by soldering material 15, Fig. 6.

The plastic body is formed of a longitudinally extending portion 16 which carries the wires 12 over the spark plugs and a central portion 17 containing the wires and extending laterally and downwardly for connection with distributor 13. The portion 17 provides a handle by which the plastic harness can be fitted onto the spark plugs and onto the distributor 13. The lower end of the portion 17 has a rounded part 18 with a recess 19 extending upwardly from its bottom and into which the distributor arm 21 extends. Wires 12 lead into the recess and have terminals 22 thereon extending from the bottom of the recess 19. In the same manner a high tension lead in wire 23 has a terminal 24 embedded in the material for contact with the center of the distributing arm 21.

10 In order that the distributor 13 can be rotated to the proper timing setting relative to the terminals 22, there is provided an adaptor 25 adapted to fit within the recess and which has terminals 26 thereon connected for engagement with the terminals 22 of the wires 12. The adaptor is secured to the distributor 13 by spring clips 27 fastened over a shoulder portion 28 on the adaptor. The adaptor has an external groove 29 into which ball bearings are inserted from an opening 31 in the rounded part 18 of the harness and are retained within this opening 31 by a plug 32 when a sufficient number of these bearings have been disposed within the groove 29. These bearings are indicated at 33. The adaptor is 15 allowed to revolve with the distributor a limited amount while still completing the circuit through the terminals of the adaptor and wires 12 without effecting the plastic harness. A complementary groove 35 is provided in the rounded portion 30 18 and in the interior wall thereof for receiving the ball bearing 33.

In order to fix the longitudinally extending portion 16 of the plastic body to the cylinder head, there are molded into the portion a plurality of 35 depending clips 36, Fig. 2, which are secured to the cylinder head by a wing headed screw 37.

A terminal 38 is embedded in the center of the adaptor 25 for engagement with the terminal 24 of the high tension wire 23.

50 While various changes may be made in the detail construction, it shall be understood that such changes shall be within the spirit and scope of the present invention as defined by the appended claim.

I claim:

A one-piece molded plastic ignition harness for gasoline engines which comprises a T-shaped molded plastic body comprising a longitudinally extending portion having ignition wires embedded therein and terminals connected with the ignition wires, said terminals being spaced in the longitudinal portion to engage with the respective spark plugs on an engine, and a central laterally extending curved portion shaped to provide a handle for said harness and having at its lower end a rounded part with a depending recess therein adapted to fit over a distributor and into which the rotating arm of said distributor extends, the wires extending through the central portion and terminals embedded in the bottom of the recess at circumferentially spaced locations therein so as to be engaged by said rotating distributor arm, and a high tension ignition wire embedded in the rounded part of said central portion and having a central terminal embedded in the center of the recess bottom, an adaptor having electrical terminals adapted when the adaptor is placed in the

recess to engage with the terminals of the wires of the harness, said adaptor being rotatably adjusted within the recess to change the timing of the ignition system and adapted to contain the distributor arm, and ball bearing elements disposed between the adaptor and the wall of the recess and positioned in complementary grooves formed therein to retain the adaptor within the recess and to render the same more easily adjustable therewithin.
